Primary Examiner — Robin Valery Webster*(74) Attorney, Agent, or Firm* — J. Bennett Mullinax,
LLC(57) **CLAIM**

The ornamental design for a hose nozzle, as shown and described.

DESCRIPTION

FIG. 1 is a top perspective view of the hose nozzle according to a first embodiment of the present design.

FIG. 2 is a top view of the hose nozzle as shown in FIG. 1; FIG. 3 is a bottom view of the hose nozzle as shown in FIG. 1;

FIG. 4 is a left side view of the hose nozzle as shown in FIG. 1;

FIG. 5 is a right side view of the hose nozzle as shown in FIG. 1;

FIG. 6 is a front view of the hose nozzle as shown in FIG. 1; and,

FIG. 7 is a rear view of the hose nozzle as shown in FIG. 1. The broken lines shown in FIGS. 1-7 are for illustrative purposes only and form no part of the claimed design.
